CLAIM

The ornamental design for a table, as shown and described.

DESCRIPTION

This application is related to commonly assigned U.S. design patent application Ser. No. 29/792,699, filed on Apr. 19, 2022, by Torres Torres et al., entitled “Table Base”; commonly assigned U.S. design patent application Ser. No. 29/792,697 filed on Apr. 19, 2022, by Torres Torres et al., entitled “Table Base”; and commonly assigned U.S. design patent application Ser. No. 29/792,698, filed on Apr. 19, 2022, by Torres Torres et al., entitled “Table”, which applications are incorporated herein by reference in their entireties.

FIG. 1 is a front right perspective view of a table according to the new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top view thereof;

FIG. 7 is a bottom view thereof;

FIG. 8 is a front right perspective view thereof;

FIG. 9 is a front right perspective view thereof; and,

FIG. 10 is a front right perspective view thereof.

The broken lines in the drawings illustrate portions of the environment and the table and form no part of the claimed design.

The long dash-short dash lines in the drawings represent a boundary of the claimed design.

1 Claim, 10 Drawing Sheets
